DESIGN FOR A GOLF OVERSHOE OR SIMILAR ARTICLE

Elliott H. Feinberg, New York, N. Y.

Application March 21, 1940, Serial No. 91,133

Term of patent 7 years

To all whom it may concern:

Be it known that I, Elliott H. Feinberg, a citizen of the United States, residing at New York city, in the Borough of Manhattan, County and State of New York, have invented a new, original, and ornamental Design for a Golf Overshoe or Similar Article, of which the following is a specification, reference being had to the accompanying drawing, forming part thereof.

Figure 1 is a perspective view of a golf overshoe or similar article, showing my new design.

I claim:

The ornamental design for a golf overshoe or similar article, as shown.

ELLIOTT H. FEINBERG.
